Application August 7, 1935, Serial No. 35,116

2 Claims. (Cl. 154—52)

This invention relates to wrappings and more particularly to a wrapping in the form of a narrow strip adapted to be wound helically about an article to form an enclosing covering therefor. 5 Such helical wrapping is of particular advantage in packaging toric articles, such, for example, as coils of wire, coils of garden hose and vehicle tires. It is much used for these purposes and highly organized machines adapted to revolve 10 the roll of wrapping material about the cross section of an article while the latter is advanced, such, for instance, as that shown in the patent to Wheildon 1,439,387, Dec. 19, 1922, are in general use. A cardinal object of my invention is to 15 provide a durable, inexpensive wrapper having various advantages in use which will appear as the description proceeds.

My invention will be well understood by reference to the following description of an illustrative embodiment thereof shown by way of example 20 in the accompanying drawing, wherein:—

Fig. 1 is a view of a toric article, such as a coil of wire, partially enclosed in a wrapping formed from a strip of material indicated as drawn from 25 a roll thereof;

Fig. 2 is an enlarged plan view of a portion of the wrapping strip with parts broken away;

Fig. 3 is an enlarged section of the same; and

Fig. 4 is a similar view showing the edges folded 30 as may be done in applying the wrapping strip to the article.

The wrapping takes the form of a narrow band, *w*, of indefinite length adapted to be packaged, if desired, in the form of a roll for use in existing 35 wrapping machines or otherwise, as indicated by the showing of such a roll adjacent a partially wrapped article, *a*, in Fig. 1. The band comprises two narrow, ribbon-like strips 5 and 7 of paper united by a layer 9 of suitable water-proofing adhesive, such as asphalt. While for 40 some purposes the band may be made in whole or in part of substantially inexpensive material, I preferably form these strips of resiliently expandable paper, as indicated by the diagrammatic showing of crappings 11. In Figs. 3 and 45 4 I have considered it unnecessary to attempt to illustrate the irregular surface produced by the crappings. Adjacent the margins of the band I may insert between the layers 5 and 7 and embedded in the asphalt 9 longitudinally extending 50 reinforcing strands 13 which may consist of cotton or jute yarns. I have here shown two yarns adjacent each edge and the edges of the strip may be folded over in application along lines about 55 between the two yarns of each pair, as illustrated

in Fig. 4, it being common to edge fold a helically applied wrapping strip. Such edge fold is usually effected by the wrapping machine in application, and thus in Fig. 1 I have shown the band *w* in the form of a roll from which it is supplied as a full width comparable to Fig. 3 and on the article to be wrapped with its edges folded, as in practice this folding would be effected during the wrapping operation as the wrapping strip is drawn from the supply roll. Yarns of the type 10 referred to have substantial stretch and, located as described, do not adversely affect the elasticity of the craped paper where such is used for the purposes intended.

Throughout the area of the band between the 15 sets of edge yarns 13, if such are used, that is, between the edges of the band and over a major portion of the width thereof and along a central zone thereof, I dispose a reinforcement which may consist of a substantially single strand 15 20 extending longitudinally in a gently sinuous curve. By referring to the strand as substantially single I distinguish between a reinforcement consisting of a number of strands interwoven or overlain one on another to form a reticulation and a strand either actually single or substantially equivalent thereto, as, for example, two strands laid side by side and manipulated as one. There are no crossings of strands in the central portion of the band to form knots or unevenness 25 30 and the reinforcement, at least along the central zone, is throughout a single thickness of strand.

The curve formed by the strand 15 is gentle, as above described, and I prefer to provide a periodicity therein substantially greater in its amplitude; that is, the distance between successive nodes adjacent the opposite edges of the band and measured parallel to its length is greater than the transverse distance between these nodes 40 measured parallel to its width. The strands thus make a relatively small angle to the length of the band, being more nearly longitudinal than transverse and yet in general extending along 45 diagonal lines.

A band reinforced as described is easily packaged in the form of rolls and easily dispensed therefrom. The sinuous nature of the strand 15 permits it to give spring-like with the expandable paper where that is utilized. In a helically wrapped package such as shown, tears may start by something catching an edge of a spire, and if one of the spires is torn apart the covering may commence to unravel and become displaced. In the present instance, if the edge is 50 55

broken and the tear starts to travel across the width of the strip, the latter may give somewhat in the manner of a spring to prevent too sudden and sharp a disrupting strain thereon. At any given place it is presented substantially diagonally to the width of the strip and the tear on striking the strand is usually diverted thereby so that the paper tears along the strand, the tear stops short or is diverted backwardly toward the opposite edge and the strip is not easily severed entirely across so that the wrapping may start to unwind.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. A wrapping in the form of a narrow band of indefinite length adapted to be helically wound about a commodity comprising a pair of strips

of paper, adhesive connecting said strips, longitudinal strands between the strips solely adjacent the margins thereof, and a substantially single, continuous, fibrous, reinforcing strand extending throughout the area between said longitudinal strands substantially as a gently sinuous, longitudinally extending curve. 5

2. A wrapping in the form of a narrow band or tape of indefinite length adapted to be helically wound about a commodity comprising a pair 10 of strips of paper adhesively connected in superposed relation and receiving between them a substantially single, continuous, fibrous strand disposed in a single longitudinal sinuous curve of an amplitude approximating the width of the 15 band but having the nodes spaced inwardly from the edges thereof, the period of the curve substantially exceeding the amplitude, the strand constituting an unreticulated reinforcement which at least along the major portion of the 20 width of the band centrally thereof is at all points of a thickness no greater than that of the strand.

HARRY W. BROWN.
